EYE-STAY ASSEMBLY FOR FABRIC
FASTENING

Louis Markin, Chicago, Ill., assignor, by mesne assignments, to Hook-Flex Company, Chicago, Ill., a copartnership

Application August 24, 1949, Serial No. 112,120

8 Claims. (Cl. 24—227)

1

This invention relates to an eye-stay assembly forming part of a fastening device of the type which is commonly used on men's clothing.

It has been the practice with the higher-priced men's clothing to use with the trousers a hook and eye at the fly to secure the two parts thereof at the top. With tailored suits it has been customary to use a special type of hook and eye, both sewed to the trousers adjacent the waist band. With increasing labor costs this is now proving to be an expensive expedient. Nevertheless this type of fastening is greatly preferred to buttons, particularly for the higher-priced men's clothing.

One shortcoming of the hook and eye type of fastening is that each of these parts is commonly anchored in position by threads which are sewn through the fabric. With continued use or extreme strain the threads will break, thereby permitting the fastening to become loose. This is a shortcoming which is also obviated by the present construction.

Primarily my invention here is concerned with the eye-stay assembly. It is complementary to a hook which, as shown, includes a tongue connected through a reverse bend with a base that is secured to the fabric by any approved means.

In the present eye-stay assembly the eye component embodies stop shoulders beyond which are prongs for penetrating the fabric and which lie flatwise thereon when turned and clinched; the stay component cooperates with such an eye by affording a base in opposition to the stop shoulders, and so placed that the fabric is disposed between the eye and stay, the prongs of the eye, when clinched, serving to secure the stay fixedly in place and to be protected thereby.

A suggestive embodiment of my invention is illustrated in the accompanying drawing, wherein:

Figure 1 is a perspective view showing a typical installation of the hook and eye on a pair of trousers;

Fig. 2 is a perspective view of one form of the eye and stay plate ready for assembly;

Fig. 3 is an elevation of the stay plate showing one form of the ends of the eye in assembled relation therewith;

Fig. 4 is an elevation of the hook and eye in locked relation;

Fig. 5 is a view in section, taken on line 5—5 of Fig. 3;

Fig. 6 is a view in section, taken on line 6—6 of Fig. 4; and

Fig. 7 which is a view similar to Fig. 3 shows an eye and stay plate of somewhat different form.

2

A typical installation of the present fastening is in connection with a pair of trousers the upper portion of which is illustrated in Fig. 1. The front fly consists of two flaps *a* and *b* to the latter of which is affixed a hook component *H* at or near the waistband. The complementary component which is carried by the fly flap *a* includes an eye *E* assembled with a stay *S* both embodying certain features which are special to this invention. In a fastening of this general character the hook is adapted to engage or disengage the eye whereby to secure the fly in closed condition or release it for opening movement.

The hook here shown is desirably produced from sheet metal which is stamped and bent to provide an arcuate tongue *10* that is reversely bent to connect with a base plate *12* wherein may be formed certain slots to define bars *13* adjacent thereto. In usual practice, the hook will be carried upon the inner face of the flap *b*, where it is fixedly secured in place as by stitching *14* which connects the bars *13* to the fabric. A suitable facing *15* may be affixed to the waistband, as shown.

25 In the present fastener the eye *E* may also be produced from sheet metal which is stamped and bent to provide a relatively flat bar *16* having opposite parallel end portions with inset stop shoulders *17* beyond which is formed a pair of prongs *18* which initially are arranged in parallelism. These prongs are adapted to penetrate the fabric in the fly flap *a*, passing inwardly therethrough from the outer face thereof. These prongs are adapted also to pass between or through guides *19* near the ends of an elongated plate constituting the stay *S* which lies upon the inner face of the flap *a*. These guides in the form shown take the form of slots closed on all four sides, as indicated clearly in Fig. 2. When the prongs have been inserted through the guide slots of the stay, the projecting end portions of the prongs may then be bent inwardly toward each other and into the space provided by a pair of medial slots *21* which are properly located for this purpose between the two end guides *19* of the stay *S*. Between each guide *19* and the proximate slot *21* the plate body is inset at *c* toward the eye *E* for a slight distance, perhaps half the thickness of the fabric ply which they penetrate (see Fig. 5), whereby to accommodate, in part at least, the prongs *18* at the point where they are extended thereacross along the inner face of the fly flap *a*. The protrusion of the prongs at these two points is materially reduced in consequence.

3
The two prongs when so disposed within the medial slots are offset relative to each other so as to be accommodated within the confines of the relatively narrow stay plate S. This may be accomplished readily by forming on one prong an elongated bevel x which faces a corresponding elongated bevel y formed on the other prong, as best shown in Fig. 3, or by elongately tapering the prongs along opposite edges (see Fig. 7) for reception in a single elongated medial slot 22. This disposition of the two prongs completely eliminates protrusion of their sharp ends by providing therefor a confining housing into which they are bent (see Fig. 5). The tapered medial slots 21 conform to the configuration of the prongs 18 and each is defined by a transverse wall, a longitudinal wall and an inclined wall connecting the longitudinal walls, and the inclined walls of the slots 18 are arranged in parallelism, as clearly illustrated in Figs. 2 and 3 of the drawings. This provides for maximum length of the prongs and maximum strength of the stay between the tapered slots 21 which accommodate the tapered prongs 18. Positioning holes 23 are shown near opposite ends of the stay plate to facilitate its placement in the correct location when the assembly operation is performed by a machine.

When the eye E and stay S are assembled, the fabric flap a will be firmly clamped therebetween. This makes for a very strong fastening which will not become loose or tear the fabric under conditions of strain. It is important that the exposed bar 16 of the eye remain spaced from the outer face of the flap a distance sufficient to permit the tongue 10 of the hook H to enter therebetween. This spacing is assured by the stop shoulders 17 at opposite ends of the eye bar which engage with the fabric.

The eye-stay assembly of my invention is desirably made of metallic flat stock. This has certain advantages. An enhanced strength may be obtained for the eye without increasing the distance of its protrusion from the face of the fabric to which it is secured. Furthermore it is reinforced so as to resist bending when subjected to strain tending to pull the eye to one side. Under such conditions the eye connection with the stay which is fixed will involve a motion on the part of the stay corresponding with that which is executed by the eye, and this adds appreciably to the resistance. While the fabric may bend to some extent, the broad base of the stay tends to oppose any undue bending movement on the part of the fabric, thus stabilizing the entire eye-stay assembly and enhancing its strength to withstand the various conditions encountered in service.

I claim:

1. For fastening a fabric fly to one flap of which is affixed a hook, an eye-stay assembly carried by the other fly flap, the eye being elongated with parallel prongs extending transversely from its opposite ends and stop shoulders at the juncture of the prongs with the eye, the prongs being adapted for insertion through the flap fabric to the extent permitted by engagement of the shoulders with one side thereof at which point the major length of the prongs is disposed to the opposite side of the fabric, and the eye between the two sets of stop shoulders being extended to lie spaced from the fabric a distance sufficient to accommodate the coating hook on the fly flap first named, and a base plate opposite the eye disposed on the fabric side

reached by the prongs consisting of an elongated stay formed medially with a slot and therebeyond, near each end, with means to guide one prong in its extension from one face of the stay to the opposite face thereof, the two prongs being bendable inwardly toward each other to lie flatwise in a single plane within the confines of the slot medially of the stay.

2. An eye-stay assembly according to claim 1 in which the slot is elongated lengthwise of the stay, and in which the length and width of the prongs is such that, when bent inwardly toward each other, each will lap the other while disposed within the confines of the elongated slot of the stay.

3. An eye-stay assembly according to claim 1 in which the slot is elongated lengthwise of the stay, and in which the length and width of the prongs is such that, when bent inwardly toward each other to lie within the confines of the elongated slot of the stay, each will lap the other while occupying more than half the width of the slot at one end thereof and less than one-half the width thereof toward the opposite end where lapping occurs.

4. For fastening a fabric fly to one flap of which is affixed a hook, an eye-stay assembly carried by the other fly flap, the eye being elongated with parallel prongs extending transversely from its opposite ends and stop shoulders at the juncture of the prongs with the eye, the prongs being adapted for insertion through the flap fabric to the extent permitted by engagement of the shoulders with one side thereof at which point the major length of the prongs is disposed to the opposite side of the fabric, and the eye between the two sets of stop shoulders being extended to lie spaced from the fabric a distance sufficient to accommodate for the full length of the space between the fabric and the eye the coating hook on the fly flap first named, and a base plate opposite the eye disposed on the fabric side reached by the prongs consisting of an elongated stay formed with a slot near each end through which a prong may be passed to guide each prong in its extension from one face of the stay to the opposite face thereof and intermediately of such guiding means with a pair of medial slots, one toward each guiding means and each positioned to receive one prong when bent inwardly longitudinally of the stay toward the other whereby the two prongs may lie flatwise in a single plane each within the confines of its associated slot, said stay being inset at points between the guide slots and the medial slots whereby the stay forms a housing to reduce obtrusion of the prongs.

5. For fastening a fabric fly to one flap of which is affixed a hook, an eye-stay assembly carried by the other fly flap, the eye being elongated with parallel prongs extending transversely from its opposite ends, the prongs being adapted for insertion through the flap fabric to the extent that the major length of the prongs is disposed to the opposite side of the fabric, and the eye between the two prongs being extended to lie spaced from the fabric a distance sufficient to accommodate the coating hook on the fly flap first named, and a base plate opposite the eye disposed on the fabric side reached by the prongs consisting of an elongated stay formed medially with a slot and therebeyond, near each end, with means to guide one prong in its extension from one face of the stay to the opposite face thereof, the two prongs being bendable inwardly toward

each other to lie flatwise in a single plane within the confines of the slot medially of the stay.

6. For fastening a fabric fly to one flap of which is affixed a hook, an eye-stay assembly carried by the other fly flap, the eye being elongated with parallel prongs extending transversely from its opposite ends and stop shoulders at the juncture of the prongs with the eye, the prongs being adapted for insertion through the flap fabric to the extent permitted by engagement of the shoulders with one side thereof at which point the major length of the prongs is disposed to the opposite side of the fabric, and the eye between the two sets of stop shoulders being extended to lie spaced from the fabric a distance sufficient to accommodate for the full length of the space between the fabric and the eye the coacting hook on the fly flap first named, and a base plate opposite the eye disposed on the fabric side reached by the prongs consisting of an elongated stay formed with a slot near each end through which a prong may be passed to guide each prong in its extension from one face of the stay to the opposite face thereof and intermediately of such guiding means with a pair of medial slots, one toward each guiding means and each positioned to receive one prong when bent inwardly longitudinally of the stay toward the other medial slot whereby the two prongs may lie flatwise in a single plane each within the confines of its associated slot, the plate, body between each guide slot and the proximate medial slot being inset toward the eye to accommodate, in part at least, the prongs extending thereacross whereby to house and to reduce the distance of their protrusion from the adjacent face of the base plate.

7. For fastening a fabric fly to one flap of which is affixed a hook, an eye-stay assembly carried by the other fly flap, the eye being elongated with parallel tapered prongs extending transversely from its opposite ends and stop shoulders at the juncture of the prongs with the eye, the prongs being adapted for insertion through the flap fabric to the extent permitted by engagement of the shoulders with one side thereof at which point the major length of the prongs is disposed to the opposite side of the fabric, and the eye between the two sets of stop shoulders being extended to lie spaced from the fabric a distance sufficient to accommodate for the full length of the space between the fabric and the eye the coacting hook on the fly flap first named, and a base plate opposite the eye disposed on the fabric side reached by the prongs consisting of an elongated stay formed with a slot near each end to guide

each prong in its extension from one face of the stay to the opposite face thereof and intermediately of such guiding slots with a pair of tapered medial slots adjacent the guiding slots positioned to receive the said prongs when bent inwardly longitudinally of the stay toward the distant end of the stay whereby the said prongs may lie flatwise in a single plane each within the confines of its associated medial slot, said tapered medial slots conforming to the configuration of the tapered prongs and the stay being inset between the guide slots and the medial slots to accommodate, in part at least, the prongs extending across the inset portions to house the prongs and reduce the distance of their protrusion from the adjacent face of the base plate.

8. For fastening a fabric fly to one flap of which is affixed a hook, an eye stay assembly carried by the other fly flap, the eye being elongated with parallel prongs extending transversely from its opposite ends, and stop shoulders at the juncture of the prongs with the eye, the prongs being adapted for insertion through the flap fabric to the extent permitted by engagement of the shoulders with one side thereof at which point the major length of the prongs is disposed to the opposite side of the fabric, and the eye between the two sets of stop shoulders being extended to lie spaced from the fabric a distance sufficient to accommodate, for the full length of the space between the eye and the fabric, the coacting hook on the fly flap first named, and a base plate opposite the eye disposed on the fabric side reached by the prongs, consisting of a stay formed near each end with a slot through which one prong may be passed to guide each prong in its extension from one face of the stay to the opposite face thereof and adjacent thereto to oppose the stop shoulders with an increased resistance, the prongs, when clinched against the stay, extending longitudinally thereof and the stay forming a housing for the prongs to reduce obtrusion of the prongs.
